Inventor:
Everett W. Kenerson,
by Edward G. Allen.

his Attest.

UNITED STATES PATENT OFFICE.

EVERETT W. KENERSON, OF HAVERHILL, MASSACHUSETTS.

ARTIFICIAL LIMB.

Application filed May 3, 1923. Serial No. 636,379.

To all whom it may concern:

Be it known that I, EVERETT W. KENERSON, a citizen of the United States of America, and a resident of Haverhill, in the county of Essex and Commonwealth of Massachusetts, have invented certain new and useful Improvements in Artificial Limbs, of which the following is a specification.

10 This invention relates to artificial limbs and more particularly to artificial arms for use in instances wherein a hand is missing and wherein the upper arm and a portion, at least, of the forearm is intact, and wherein in a joint or hinge is included in the make-up of the limb to enable it to perform its proper function.

An object of the invention is to produce a limb of this class which has a portion 20 thereof adapted to be swung with respect to other portions, and having means coacting with said movable portions adapted to permit said swinging movement, said means being of such construction and arrangement 25 as to afford relative longitudinal adjustment between the said movable portions.

Another object of the invention is to so arrange the adjusting means that adjustment may take place while the limb is attached to the user, and by one hand of the user without the assistance of others.

A further object of the invention is to provide simple pivotal connection between the movable portions which may be adjusted 35 to the required position, and retained therein, until it is desired to make a change.

It is a further object of the invention to produce an artificial limb that is strong and durable yet light in weight and in which the pivotal connection is not bulky and cumbersome but is simple and accessible for ready adjustment.

So far as is known, in artificial limbs of this class, it has not heretofore been possible to relatively adjust, toward or from each other, two parts, such as the upper arm and forearm parts, the pivotal connection being of such arrangement that relative longitudinal movement of the parts was not 50 possible.

Generally the pivotal connections were actually fixed pivots and not susceptible to ad-

justment, and consequently considerable inconvenience was at times experienced in applying the artificial limb to the natural limb, 55 because of the fact that adjustment of the pivotal center was not possible.

Another feature of the invention consists in the use of a resilient member adapted to encircle the natural limb when the artificial limb is applied thereto. This member enables the artificial limb to be applied, by opening, when the natural limb is inserted, and is arranged to thereafter hug the natural limb to thereby facilitate in securing 65 the artificial member to the natural member, which has been found to be a great convenience, as it automatically holds the portion of the artificial limb that is to be secured, in position to have the securing 70 means attached, whether said means consists of straps and buckles, or, as in the present instance, a cord.

As it is a feature of this invention to produce an artificial limb that is strong and 75 durable and yet light in weight, certain portions of the present device are made of aluminum, while an extremity thereof, such as a hand, is composed of a light, compact, easily moulded mass of preferably fibrous 80 material, such as felt, or its equivalent.

It is also an object of the invention to provide a hand the digits of which may be flexed without injury thereto, and which will return to the normal positions thereof 85 when released.

A further object of the invention is to provide a simple, inexpensive, and efficient spring means to enable the digits to be flexed and which does not require means to 90 retain them in place other than the material of which the hand is made.

The invention further consists in certain novel features of construction and arrangement of parts which will be fully understood from a description of the drawings and the claims hereinafter given.

Of the drawings:

Figure 1 represents in elevation, partially broken away, one form of artificial limb embodying the invention.

Figure 2 an elevation looking in the direction of arrow A Figure 1.

Figure 3 shows a portion of the limb as

seen in Figure 1 but with the forearm part moved into another position.

Figure 4 a detail of one of the pivotal connections as seen in Figure 1, the cover plate being removed.

Figure 5 a detail similar to Figure 4 showing the slidable pivotal connection.

Figure 6 an enlarged section on the line 6—6 Figure 1.

10 Figure 7 an end view looking toward the right Figure 2 showing the approximate position of the arm encircling band before being applied to the natural limb.

15 Figure 8 a view looking at the back of the hand, partially broken away, prior to bending the digits.

Figure 9 a section on the line 9—9 Figure 8.

20 Figure 10 a view similar to Figure 9 showing one of the digits bent as it might appear in the finished hand.

Figure 11 a section on the line 11—11 Figure 9.

25 Like characters represent like parts throughout the several figures of the drawings.

Referring to the drawings:

30 The drawings herewith illustrate the invention as applied to one form of artificial limb, but it is obvious that the principle might be applied to other forms without departing from its spirit and scope.

35 In the present instance a cuff 10, made preferably of aluminum and suitably covered with leather is adapted to receive within it a socket-like extension 11 of a hand 12. The said cuff being of a shape somewhat conical to conform to that of the natural member, its longitudinal edges 13 being separated as seen in Figure 2, the gap being closed by an extension of the material of the cuff cover.

40 The extension 11 of the hand 12 having the socket 14 for the forearm stump has a raised portion or hump 15 made to resemble the wrist bone, and as the cuff 10 extends thereover, it will be readily seen that it offers aid in securing the hand and cuff in assembled position. To further secure the 45 hand to the cuff, a lacing 16 is provided, which when initially secured to the satisfaction of the user need not be disturbed thereafter when removing or replacing the limb; and when the conical shape of the cuff and extension 11 is taken into consideration it will be seen that the hand may be firmly secured to the cuff.

45 In order to hold the cuff and hand to the arm of the user, a second cuff or band 17 is provided which is preferably made of leather or like material, having a ribbon of spring metal R secured in a hem as seen at the upper or left end in Figures 1, 2, and 7.

The band 17 is provided with a lacing

18 similar to that of the cuff 10, both of which are so arranged that they may be secured by the good hand of the user without assistance.

The connections between the cuff and the band are such as to permit of relative swinging movements between these two parts. In the present invention the cuff has fast there-to at approximately diametrically opposite points, metallic plates 19 fastened at 20 in any suitable or convenient manner.

70 Fast to the band 17 are the plates 21 and also one end of the plates 22 and 23, between which latter are mounted the trucks or rolls 24, 25 and 26.

75 The roll 25 is mounted on the stud which secures the plates 21, 22 and 23 to the band 17, the roll 26 is mounted on the stud which secures the plates 22 and 23 together, while the roll 24 is mounted on the stud which secures the plates 21, 22, and 23 together and which also serves as a pivot around which either of the limb parts may swing.

80 It will be understood that the studs are so arranged as to properly secure the said plates and yet permit freedom of movement of the rolls 24, 25 and 26.

85 The plates 21 and 22 are separated sufficiently to receive between them the ends of plates 19, see Figures 2 and 6.

90 The plates 19 are provided with elongated slots 30 through which the studs of rolls 24 pass to form the pivotal connections between the cuff 10 and band 17.

95 To longitudinally adjust the cuff and band toward or from each other the stud and slot connection is preferably used but it will be obvious that other means might be employed without departing from the spirit and scope of the invention.

100 To accomplish the adjustment and to retain the studs in their adjusted positions relatively to the slots 30, a cord 31 is used, which is secured to the cuff 10 at 32 and passes between the plates 22 and 23 outside of the roll 24, around roll 25, and inside of roll 26 to fastening means 33 such as oppositely arranged lacing hooks on the cuff 10.

105 It will be readily seen that if it is desired to increase the distance between the cuff and band, the cords 31 will be released from the hooks 33 and slack given which will enable the studs of rolls 24 to be shifted to new positions in the slots 30. If the distance is to be lessened the cords will be pulled till the stud is in the desired location, and again refastened.

110 The locations of the rolls 24, 25, and 26 are such, that when the limb is in use, and the natural arm is bent, as at the elbow, see Figure 3, to whatever degree, the cords 115 31 will be caused to maintain their initial tensions uniformly and continuously. This is due to great extent to the location of

the rolls 26 which alternately take up, and give slack to the cords during the bending and straightening movements of the arm.

In practice it is preferred that a glove 35 shall be placed on the hand to thereby conceal the cuff lacing which extends nearly to the end of the cuff at the wrist portion.

The hand shown in Figures 8-11 inclusive is preferably made of felt moulded to 10 the desired size and shape and having a socket 14 to receive in the present instance the stump of a forearm.

As shown in Figures 1 and 2 the digits are made to assume a natural position which 15 enables the user to accomplish a number of feats which can not be successfully accomplished when a hand having rigid digits is used.

While the main body of the hand 12 is 20 comparatively rigid, the digits are flexible to a degree which permits the use of the hand to carry articles of various descriptions such as a pocketbook, handkerchief, or small parcels, and even permits a pencil 25 or pen to be held in a natural position for the purpose of writing.

In order to give the necessary strength to the digits and yet permit flexing thereof, a length of preferably flat spring metal 36 is 30 inserted into each one.

This spring metal 36 is inserted after the hand is formed, the spring being pointed as at 37 is forced into the digit until the pointed end is well into the comparatively 35 rigid body of the hand, and its other end inside the digit tip.

When all the digits have been provided with springs, they are bent to the positions required, as for instance in Figure 9, which 40 action automatically locks the springs in place by reason of the numerous bends which prevent the withdrawal of the said springs.

In applying the artificial limb to the user it will be supposed that the lacing 16 45 has been secured in the proper manner to hold the hand to the cuff and for the comfort of the user.

The lacing 18 being loosened and disengaged from its fastening hooks, the band 17 50 is ready to receive the arm which may be thrust through the band till the stump properly seats in the socket 14.

The band 17, which is preferably made of leather and somewhat lacking in stiffness, will at this time, be held quite snugly 55 encircling the upper arm by reason of the circularly arranged spring ribbon R in the end thereof, so that the lacing 18 may be readily engaged with the fastening hooks 60 and secured with but little trouble and effort.

When the stump has been seated in the socket and it is found that the band 17 is not in its accustomed comfortable position

on the arm, or that the pivotal connection 65 does not approximate closely enough a working position with the elbow joint, the cords 31 may be slackened or shortened as the circumstances require to change the position of the studs of the rolls 24 in the 70 slot 30.

By this means it is possible to shift the pivotal points at any time while the limb is applied to the user, in order to locate them 75 to the best advantage to perform the proper function, and the use of a tool is not required.

It is not known that a joint or pivotal point of this sort has ever been used in connection with an artificial limb, and therefore 80 it is not the intention to limit this invention to the precise construction and arrangement shown as it is obvious that various changes might be made therein without departing from its spirit and scope.

Having described the invention I claim:

1. In a multipart artificial limb, portions of which are required to be swung relatively to other portions; pivotal connections between said portions; means to shift said 90 pivotal connections whereby said portions may be adjusted toward or from each other; and means to retain said portions in adjusted position.

2. In a multipart artificial limb portions 95 of which are required to be swung relatively to other portions; pivotal connections between said portions; means to adjust said portions toward or from each other said means including said pivotal connections; 100 and means to retain said portions in adjusted position.

3. In a multipart artificial limb portions of which are required to be swung relatively 105 to other portions; pivotal connections between said portions adapted to be shifted for the adjustment of said portions toward and from each other; and flexible means adapted to be attached to said portions to thereby retain them in adjusted position.

4. In a multipart artificial limb portions of which are required to be swung relatively to the other portion; pivotal connections between said portions adapted to be shifted for the adjustment of said portions toward 110 and from each other; flexible means adapted to be secured to said portions to thereby retain them in adjusted position; and means whereby said flexible means will be caused to maintain a constant uniform tension regardless of the relative positions of said portions.

5. In an artificial limb of the class described portions of which are required to be 115 swung relatively to other portions, pivotal connection between said portions adapted to be shifted for adjustment of said portions toward and from each other; flexible means 120

secured to one of said portions and engaging another of said portions adapted to maintain said pivotal connection in the required position; and means whereby a continuous uniform tension may be applied to said flexible means regardless of the relative positions of said portions.

6. In an artificial limb of the class described having two members thereof pivotally connected together, plates extending from each member adapted to coact to form said pivotal connection; said pivotal connection being composed of slot and stud engagement between said plates; means to maintain said slot and stud engagement; and means to vary the distance between said members through said slot and stud engagement.

7. In an artificial limb of the class described having two members thereof pivotally connected together, plates extending from each member adapted to coact to form said pivotal connection; pivotal connection comprising slot and stud engagement between said plates; flexible means coacting with said pivotal connection and adapted to vary the relative distance between said members; and coacting with means to create continuous uniform tension in said flexible means regardless of the relative positions of said members.

8. In an artificial limb of the class described having two members adapted to be pivotally joined together, a plurality of plates extending from each of said members arranged to overlap those of the other member; certain of said plates of one member having slots therein; certain other of said plates of the other member having pivot studs carried thereby, adapted to shiftably engage said slots, for the purpose of adjustment between the said two members; flexible connections between said members fast with one of said members and adapted to control the positions of said studs in said slots; and coacting with means to effect continuous uniform tension on said flexible connection regardless of the positions of said members.

9. In an artificial limb of the class described having two members adapted to be pivotally joined together, a plurality of plates extending from each of said members arranged to overlap those of the other member; certain of said plates having slots therein; certain other of said plates having studs carried thereby adapted to shiftably engage said slots; certain of said plates being so arranged as to maintain said slot and stud engagement; a plurality of trucks carried by one of said members; flexible connections between said members adapted to shift said studs in said slots and maintain them in position, said trucks acting in conjunction with said flexible connections for said purpose and being of such arrangement

as to maintain continuous uniform tension on said flexible connections regardless of the positions of said members.

10. In an artificial limb of the class described having two members adapted to be pivotally connected, plates arranged in pairs carried by one of said members and projecting therefrom; plates carried by the other member and projecting therefrom and adapted to be pivotally swung between the plates of said pairs; studs carried by said first mentioned plates; said second plates having slots therein adapted to coact with said studs to form shiftable pivot points; a flexible connection between said members; trucks carried by one of said members adapted to coact with said flexible connection to shift said studs in said slots said trucks being so arranged as to equalize the tension of said flexible connection during the pivotal movements of said members.

11. In an artificial limb of the class described having two members thereof adapted to be pivotally connected, a member adapted to receive the stump of a natural limb; a member adapted to be secured to another portion of said natural limb; shiftable pivotal connections between said members; means coacting with said pivotal connections whereby said members may be adjusted toward or from each other; limb embracing means forming part of said second member adapted to normally retain said second member in limb embracing position; and means to further secure said second member to said natural limb.

12. In an artificial limb of the class described having two members thereof adapted to be pivotally swung, a member adapted to receive the stump of a natural limb; a member adapted to be secured to another portion of said natural limb; shiftable pivotal connections between said members; means coacting with said pivotal connections whereby said members may be adjusted toward and from each other; a nether extremity such as a hand carried by said stump receiving member; means to secure said extremity to said receiving member; a plurality of springs in said extremity adapted and arranged to furnish resiliency to certain portions of said extremity such as fingers; and means to secure said second member to said natural limb.

13. In an artificial limb of the class described having two members thereof adapted to be pivotally connected together, a conical member adapted to receive the stump of a natural limb; a member adapted to be secured to another portion of said natural limb; pivotal means between said members adapted to be shifted for the purpose of relative longitudinal adjustment between the said members; a nether extremity comprising portions such as a wrist, hand, and

5 fingers integrally formed and having a conical portion adapted to be secured within said stump receiving member; said wrist portion having a socket therein to receive the end of a stump; means to secure said extremity to said stump receiving member and to a stump; shaped springs adapted to be inserted in said extremity after the formation thereof and adapted to furnish 10 strength and resiliency to certain portions of said extremity such as fingers; and means to secure said second member to said natural limb.

14. In an artificial limb having members 15 thereof adapted to be articulated, a nether extremity such as a hand having a wrist portion and fingers integral therewith and composed of fibrous material and having reinforcing resilient material inserted therein 20 and extending to said fingers whereby said portions may be made to assume certain positions and return in a resilient manner, said wrist portion having a socket therein to receive the stump of a natural limb.

25 15. An artificial limb having members thereof adapted to be pivotally joined together; shiftable pivotal connections between said members; means to retain said connections in their required positions; col- 30 lapsible means coacting with one of said

members adapted to embrace a natural limb for the purpose of temporarily securing the artificial limb thereto when it is to be adjusted for use; and means to further secure said member to said natural limb when the 35 said artificial limb is adjusted for use.

16. An artificial limb having an upper arm and a forearm part adapted to be pivotally connected by shiftable pivot means; means to retain said pivot means in the required position; and a normally collapsed spring band in said upper arm portion adapted to be expanded to initially secure 40 said upper arm portion to an arm; and means to further secure said upper arm part 45 to an arm.

17. An artificial limb having upper and fore arm parts adapted to be pivotally connected; a normally collapsed spring band adapted to be expanded to encircle an arm 50 to initially secure said upper arm part to an arm; a secondary securing means such as a lacing adapted to finally secure said upper arm part to an arm; shiftable pivot connections between said upper and fore arm 55 parts; and means to retain said pivotal connections in the required positions.

Signed by me at Boston, Massachusetts,
this 2nd day of May, 1923.

EVERETT W. KENERSON.
